(57) **CLAIM**

We claim the ornamental design for an electrical-box cover, as shown and described.

DESCRIPTION

FIG. 1 is a top right perspective view of an electrical-box cover showing the design;

FIG. 2 is a top plan view of the electrical-box cover of FIG. 1;

FIG. 3 is a left side elevation view of the electrical-box cover of FIG. 1;

FIG. 4 is a right side elevation view of the electrical-box cover of FIG. 1;

FIG. 5 is a rear elevation view of the electrical-box cover of FIG. 1; and,

FIG. 6 is a front elevation view of the electrical-box cover of FIG. 1.

The broken lines shown in the figures represent unclaimed subject matter and form no part of the claimed design. The portion of the article that is not shown in the figures is not claimed. The claimed design includes no portion that would be shown in a bottom plan view, hence a bottom plan view is not included in the drawings. The relatively light and thin shade lines show contour and not surface decoration.

1 Claim, 3 Drawing Sheets
